UNITED STATES PATENT OFFICE.

PAUL NORTII, OF CLEVELAND, OHIO, ASSIGNOR TO THE CLEVELAND TARGET COMPANY, OF SAME PLACE.

DESIGN FOR A TARGET.

SPECIFICATION forming part of Design No. 28,298, dated February 15, 1898.

Application filed November 8, 1897. Serial No. 657,887. Term of patent 14 years.

To all whom it may concern:

Be it known that I, PAUL NORTH, a citizen of the United States, residing at Cleveland, in the county of Cuyahoga and State of Ohio, 5 have invented and produced a new and original Design for a Target, of which the following is a full, clear, and exact description, reference being had to the accompanying drawing.

The target is a printed plain surface, like 10 a map or chart, and is designed to be hung or otherwise secured in a vertical position, and the drawing is a front elevation of the target when so placed.

The target consists, essentially, of a surface 15 covered with representations of flying targets, which are about the shape of an inverted sauce-dish.

The target shown in the drawing is a circle 20 having at its center a bull's-eye of different color from the background, the bull's-eye being one solid color, as black. Between the

periphery of the circle and the bull's-eye are represented a large number of clay pigeons, which are in perspective and are shown in outline only. These flying targets, which on 25 the target are figures of more or less elliptical shape, may or may not be in the same color as the bull's-eye, but they should be of different color from the background.

Referring to the parts by letters, A represents the background of the target, B the bull's-eye, and C the clay pigeons.

Having described my invention, I claim—
The design for a target, substantially as 30 herein shown and described.

In testimony whereof I affix my signature 35 in presence of two witnesses.

PAUL NORTII.
